(57) **CLAIM**

The ornamental design for an induction cooktop, as shown and described.

DESCRIPTION

FIG. 1 is a perspective view of an induction cooktop showing our new design;

FIG. 2 is a top plan view thereof;

FIG. 3 is a bottom plan view thereof;

FIG. 4 is a front elevational view thereof;

FIG. 5 is a right side elevational view thereof;

FIG. 6 is a left side elevational view thereof;

FIG. 7 is a rear elevational view thereof; and,

(Continued)

FIG. 8 is an enlarged top plan view of a section defined by lines 8-8 of FIG. 2.

The broken lines in the drawings illustrate portions of the induction cooktop that form no part of the claimed design. The dash-dotted lines in the drawings define the boundaries of the claimed design or the outline of the enlarged view.
